WIRE COATING APPARATUS

Albert T. Candy, Jr., Oak Park, Ill., assignor to
 Candy & Company, Inc., Chicago, Ill., a corpora-
 tion of Illinois

Application November 19, 1932, Serial No. 643,307

5 Claims. (Cl. 91—32)

My invention relates to apparatus for coating wires or the like and especially for applying to an insulated wire an extremely thin coating of wax-like material even though it be applied over a 5 layer or impregnation of similar material. This is of advantage in making possible the production of colored wire without the expense of a thick impregnation or layer of material containing the costly pigments.

10 While certain features of my invention are applicable to impregnation of a continuous strand-like material, it is particularly concerned with the problem of coating where the material to be deposited is coated as a film of substantially 15 the same or slightly larger coated diameter than the object being coated. Many features of my invention are applicable to continuous coating processes for strand-like objects other than wire, but I here illustrate it particularly applied to insulated wire for electrical purposes. As applied 20 to insulated wire, my application is specifically concerned with coating an insulated wire, the fabric braid of which has previously been impregnated.

25 In insulated wire, the fabric braid has customarily been impregnated with a weather proofing material—frequently a wax-like material such as paraffin or a pitch such as asphaltum pitch—to protect the rubber insulation beneath the braid.

30 More recently stearin pitch, or some other flame-retarding composition has been used either as the impregnation or as an auxiliary coating on the previously mentioned impregnation, to check the tendency of the braid to sustain combustion and 35 carry flame along the wire in the event of fire. When the impregnation or resulting surface has been pitch-like, the wire has been given a final coating of paraffin to restore the surface characteristics of the wire which were found desirable 40 when the braid was treated only with a paraffin impregnation. The desirable characteristics of the paraffin or other wax-like surface are its lubricating qualities, which enable the wire to be drawn through circuitous conduits without danger 45 of abrasion, and a generally non-sticky surface, which avoids danger of the convolutions of wire on a spool or coil sticking together in warm weather as would be the case with a pitchy surface.

50 A paraffin coating or pitch has certain objections, even apart from the difficulties of applying it properly, among them: the paraffin, while normally transparent, has a tendency to flake off and also to form more or less opaque regions 55 where it has been subjected to incidental scrap-

ing action, with the result that the appearance is not uniform and to a greater or less extent any color beneath the coating is dulled; the die or wiper through which the paraffin coated wire is passed often acts unevenly leaving bared or even abraded regions on the braid; the coating may be contaminated with the impregnation or other underlying material; the paraffin is inflammable and therefore in any event a very objectionable feature, making it necessary to keep the 10 paraffin film at a minimum of thickness; and, considering the ultimate diameter of the wire as the working limit, whatever thickness is taken up by the paraffin film is so much less thickness of 15 fire-retarding material. It has also been proposed to impregnate the braid with paraffin or a substitute wax and to coat this with a flame-stop material such as stearin pitch, the theory being that the melted stearin pitch, being applied at a higher temperature than the melting point of the 20 paraffin, will melt the paraffin and some of it will find its way through the coating of stearin pitch sufficiently to make the surface of the coating non-sticky without destroying its fire-retarding 25 quality. This also has its objections: the difficulty of controlling the intermixture of the paraffin with the pitch; the inability to secure a uniform mixture of the paraffin throughout the coating, for the minimum content of paraffin will obviously be at the surface and that if sufficient 30 to serve its function there, there is an excess of paraffin further in from the outer surface of the coating which would destroy the flame-retarding 35 quality of the coating at such regions, and thereby cut down its total fire-retarding effectiveness; 40 the braid is left, for the most part, wholly impregnated with the paraffin which constitutes virtually a candle the burning of which is checked only by a very thin film of fire-retarding material which itself has, for the most part, too great a 45 paraffin content to be effective; and the inability to produce colored wire without greatly increased cost.

One object of my invention is to provide and produce a wire which overcomes these objections 45 in paraffin-over-pitch and in pitch-over-paraffin wires, but which will still give the desired non-sticky, lubricated, "slick finished" surface while retaining a relatively fire-retarding character.

I achieve this solution to the problem by using 50 an impregnation and a coating, the compositions of which in general are substantially the same or at least wherein the impregnation is as non-sticky as the coating and the coating is as flame-retarding as the impregnation. To this end, 55

the impregnation and coating compositions which I use preferably contain both stearin pitch, or a substitute, and paraffin, or a substitute, there being enough wax-like material to make 5 the composition non-sticky and slippery and to impart a "slick finish" and enough stearin pitch or a substitute to make the composition nevertheless sufficiently flame-retarding. Apart from the aspect of coloring the wire (which I shall 10 presently discuss), the advantages of using a coating composition having substantially the formula or characteristics of the impregnation, as compared with a coating of paraffin or substitute wax-like material, include: The greater 15 flexibility of the coating; more fire repellent protection; elimination of inflammable surface film; better binding of the coating to the impregnation; and rendering immaterial the possibility of contamination between the coating and 20 impregnation.

Referring now to the problem of code wire in the assortment of colors required by the trade, where the impregnation composition includes pitch—and stearin pitch is most frequently used 25 to give a flame-retarding character to the wire—the color given the wire is black, or at least very dark. Pigments are too expensive to make it feasible to add sufficient quantities to the impregnation composition. Hence it has been proposed to paint the impregnated wire before adding the transparent paraffin coating. This has numerous objections: the added expense of another process; the cost of the paint itself; the cost of the additional apparatus necessary for the 30 paint dipping; the dulling effect of the paraffin, even though normally transparent, over a bright color; the increased tendency toward white flakey superficial appearance of the paraffin coating and its tendency to flake off—due to 35 the poor binding with the smooth surface of the paint; and, in some instances, crumbling of the paint itself.

Thus another object of my invention is the provision and production of a wire which is colored, wherein these objections are avoided and where the additional expense of coloring the wire is minimized and the color is made of lasting brightness without danger of streaking by superficial abrasion. To this end, I use, in so far 45 as practicable, the same base composition or formula for the impregnation that I do for the coating and I add the pigment to the coating only. This gives an ample thickness of colored film, but as the amount of coating composition used 50 per thousand feet of wire is considerably less than the amount of impregnation used per thousand feet, a great saving in the cost of pigment is effected as compared with the coloring of both compositions or the use of a colored impregnation omitting a coating. My composition, when 55 used for a colored coating, has a natural opaqueness which lessens the amount of pigment required.

My invention is also concerned with the 60 method or technique of coating. The method is claimed in my Patent Number 1,891,501 of December 20, 1932, of which this application is a continuation in part. The usual method of coating a wire has been to pass a considerable length 65 of the wire back and forth over sheaves through a sizeable vat containing the melted coating material, pass the strand or wire through a die, wiper or similar device to remove the excess material and to control the thickness of the coating, and then to dry it by air passing the wire 70

over sheaves for a distance of some thirty to 75 seventy-five feet. Some of the objections to coating by dipping are: the wire remains in the melted coating composition long enough to permit heat to be imparted to the impregnation to a point of injuring it; the coating material may be contaminated by the impregnation; the excess coating must be removed down to the desired 10 diameter or thickness of film; the die or other means of removing the excess coating may cut 15 through the coating and bare the impregnation; the resulting finish must be a dull, wiped surface whether or not that kind of a finish is desired; and, because the wires pass back and forth through the vat containing the coating material, it is difficult to provide proper agitators to 20 keep the material uniform without interfering with the wire, and therefore the composition as coated often varies due to the settling out of 25

Another method of treating, somewhat different from the dipping process, has been to pass the strand through a vat or receptacle containing the melted coating material and then—instead of passing wire up through the surface of the 25 liquid and to the die or scraper—to pass the wire directly through a discharge die in the side wall of the vat or receptacle. From the discharge die, the wire emerges directly into cooling water or passes through a long reach 30 through cool air to a sheave. Such methods have been used principally for impregnations. If used for coatings, they would be subject to numerous objections: To keep the melted material from running out through the discharge 35 bore as the wire is pulled through, the bore has to be small enough to compress or squeeze the immersed wire sufficiently to scour the bore of the die. Unless the wire is squeezed so that the 40 braid or solid part of the wire scours the bore of the die, the relatively cooler die will cause the material to congeal and deposit within its bore. This internal deposit on the bore builds up until the scouring action again takes place against the 45 braid. Thus no control is had for the thickness of the film of material beyond the diameter of the braid. The scouring action also increases the tension necessary to draw the wire through the die. These methods would not operate effectively 50 for coating even if the diameter of the bore of the discharge die were greater than that of the braid, for the following reason: The hot impregnation material—whether applied simultaneously with, or immediately preceding, the coating layer—would be absorbed in so great an amount per 55 foot of wire that the resulting temperatures at the outer regions of the wire at the braid would be too high to congeal the material being applied. The die would be relatively colder. As a result 60 the fluidity, through a cross section of the bore of the die, would be greatest—not at the surface of the bore—but at a region radially inwardly of the surface of the bore. The rapidly moving wire and the stationary parts of the die would 65 part at the region of greatest fluidity. Since this would not be at the surface of the bore, but rather at the surface of the braid, the material could not be applied to a substantially greater 70 diameter than the thickness of the braid, and in any event it would not be accurately controlled.

Another objection to the use of these treating processes for coating relates to the problem of cooling or setting the coated material. It is necessary that the coated material set before it touches the sheave or other metal part. If the 75

wire is to be cooled by air after it emerges from the die, a very large amount of floor space must be taken up with one straight reach of wire some thirty to seventy-five feet long before it comes 5 to its first sheave. In those methods where the wire emerges from the die directly into a bath of cooling water, the water further chills the discharge end of the die, building up a restrictive neck within the end of the 10 bore of the die, due to its increased congealing action with the result, already explained, of scraping the material to be deposited down to the surface of the braid. Another objection to these processes is that it is necessary to have a coating 15 material which melts at a lower temperature than the impregnation material.

A further object of my invention is an improved method of coating which eliminates these objections. More specifically the objects include: 20 a uniform controlled thickness of coating film; less tension for pulling the wire through the apparatus; greater permissible speed; permitting the use of a coating material with the same or higher melting point than that of the impregnation; 25 the use of a tempering bath of water without chilling the die with its consequent objections and before touching any metal parts such as a sheave; a slick "flame" finish for the coated wire; less dribble from the die; practically no scrapings 30 to be returned for remelting; and adaptability to oblique or vertical positions for the traveling wire.

In the method by which I achieved these objects, I preferably pass a wire, the braid of which has 35 been previously impregnated and cooled, a short distance through a melted body of the coating composition and thence discharge the wire through a bore of substantially the diameter desired on the finished product, through a short 40 intervening air gap, down through the surface of, and into the body of, a tank of tempering water where it passes over sheaves and on to the winding spool. The bore of the discharge die is kept at a 45 temperature higher than the melting point of the coating material. No cooling water comes in contact with the discharge end of the die. Hence its temperature throughout is in excess of the melting point of the coating material. The wire and its impregnation, being previously cooled, 50 of less temperature than the melting point of the coating material. Therefore it congeals a layer of coating material upon itself. The length of wire exposed at any one moment to the melted coating material is too short and the speed at 55 which the wire passes is too great, to permit the body of the wire and its impregnation to be heated to any appreciable extent by the momentary submersion in the melted coating composition. Therefore, as the wire passes through the 60 coating apparatus, the body of the wire and the impregnation do not rise in temperature enough to relinquish, by melting, the layer of coating material which has deposited upon it, but continues to accumulate a congealed layer of the material. 65 Should this congealed layer be of greater diameter than the bore of the hot die, the layer is either scraped or melted down to the bore of the die and passes through the die with the dividing or parting at the surface of the bore. 70 Preferably, however, the various factors are so controlled that by the time the wire enters the bore of the discharge die, the layer of congealed material has not built up to the diameter of the bore, but leaves a substantial film of liquid melted 75 material therebetween, which film is preferably

lessered toward the discharge end of the bore by the continued accumulation or increase of the layer of congealed material. The melted material immediately adjacent the surface makes an effective lubricant for the easy and rapid passage 5 of the wire.

For commercial code wire the diameter of the bore of the die may be .012 inches greater than the diameter of the impregnated braid as it enters the apparatus. This provides a coating film of 10 approximately .006 inches thick. As the wire emerges from the discharge end of the bore the greater portion of the thickness of the coating is in congealed form. The remaining portion is so thin a film that it also congeals so quickly 15 that there is no opportunity for it to accumulate eccentrically of the wire or to drop from the wire.

However, it is not necessary that the bore of the die be larger than that of the incoming wire to be coated. In fact I prefer, as herein after 20 disclosed, in applying a very thin coating to use a discharge die of a bore of the same size or even a trifle smaller than the incoming wire. This may be done when the incoming wire is compressible. In code wire where there is a braided jacket 25 over rubber insulation, the wire is permanently ensmalled by forcing the braid into the rubber insulation. Thus I am enabled to take an impregnated or coated wire of a given diameter and apply to it an additional coat without increasing 30 the diameter. And this coating may be a color coating of a wax-like compound like that of the undercoat or the impregnation.

This is of especial advantage in making the 35 two color coded wire disclosed in my copending application Serial No. 642,378 filed November 12, 1932. My present application is also a division thereof as to the apparatus. In said copending application I have shown a series of wires for code work wherein the different colors used may 40 be confined to only a few readily distinguished colors but still provide for a large number of readily distinguished wires. This I do preferably by the use of two color coatings—an under coating of one color and an outer coating of a different color—which are combined in different combinations. Fully to identify a given wire, a small region of the outer coating is scraped away to reveal the color of the under coating. Using eight 45 primary colors, this gives some sixty-four different combinations. By using three color coatings, some five hundred different combinations are possible. As an alternative, instead of a full outer color coating, a colored streak may be applied. 50

The present application is concerned primarily with apparatus for carrying out the previously described methods and for making the above described wire products. The apparatus herein disclosed is not however necessarily limited to such specific method or product. 55

The foregoing with further objects, features and advantages of my invention are set forth in the following description of a specific preferred embodiment thereof reference being made to the accompanying drawings wherein:

Fig. 1 is a side elevation of the coating apparatus of my invention with its associated supply reel, tempering tank and winding reel; 70

Fig. 2 is a plan view thereof;

Fig. 3 is a detail view of a portion of the apparatus shown in Fig. 1 but on an enlarged scale, the coating material reservoir being broken into longitudinal vertical section; 75

Fig. 4 is a longitudinal vertical section of the applicator itself;

Fig. 5 is a transverse section taken on the line 5—5 of Fig. 3 through the applicator and showing the control valve;

Fig. 6 is a detail elevation of the valve taken on the line 6—6 of Fig. 5;

Fig. 7 is more or less a diagrammatic longitudinal section through the bore 26b of the discharge die 26 and upon a greatly enlarged scale;

Fig. 8 is a side elevation of a portion of the finished wire product with the several layers progressively removed;

Fig. 9 is similar to Fig. 8, but shows a modified form of wire wherein an outer colored streak rather than a full color coating is applied to the surface of the wire; and

Fig. 10 is a cross section similar to Fig. 5, but including only the chamber of the applicator and showing a modified construction adapted to the application of an outer streak such as shown in Fig. 9.

The apparatus shown in Fig. 1 comprises a supply reel of wire 10 to be coated, the reel 11 being mounted to unwind as it rotates against the retarding influence of the usual friction brake 12, which may be a weighted rope wrapped one or two turns about the shaft of the reel. From the reel the wire 10 is led over a sheave 13 mounted on a suitable frame 14 and through the applicator 15 down into a tempering tank 16, entering the body of tempering water 17 obliquely through its surface, thence over sheaves 18 and 19 within the vat, over a final sheave 20 and to the winding reel 21 which is driven by a pulley 22 and belt 23 from a convenient source of power. The applicator 15, referring to Fig. 4, comprises a body, which may be of steel, penetrated by a longitudinal hole 24. One end of the hole 24 is closely fitted or plugged by a cylindrical anterior die 25 and the other end by a posterior or discharge die 26. A cylindrical chamber 27 is left between the two dies. As shown in the transverse section of Fig. 5 the applicator body may be split on a plane along the axis of the dies leaving lower and upper body members 28 and 28' held together by cap screws 29 and aligned by suitable dowels. The purpose in halving the body is to facilitate cleaning and the removal or substitution of the dies.

The dies have aligned central bores 25b and 26b respectively. The diameter of the discharge bore 26b is substantially that of the desired overall diameter of the coated wire. The diameter of the discharge bore 26b may be that of the incoming wire plus the coating to be deposited on it, as illustrated in my said patent; but it is also possible and in some instances preferable, as here illustrated, to have the discharge bore 26b of the same diameter as the incoming wire. In that case a shorter bore is more satisfactory.

The anterior bore 25b is conveniently and preferably slightly greater than the diameter of the entering wire. The applicator is mounted obliquely on the frame 14 in such position that the center line of the bores coincides with the center line of the straight region of wire determined by the sheave 13 and the water vat sheave 18.

As shown in Fig. 5 there is a communication between the chamber 27 of the applicator and the bottom of hopper-like reservoir 30 by means of the pipe connections 31 and 32 and a cut-off valve 33. The reservoir 30 is either round, or as here shown, square in cross section, the lower part being of inverted truncated pyramidal

form. The reservoir 30 is divided into an inner chamber 30; and an outer chamber 30 by a partition 34 of perforated sheet metal. The partition 34 is of square perimeter with its lower edges contacting the sloping sides of the hopper portion of the reservoir 30 and the upper edges extending to the top of the reservoir. The reservoir is heated to keep the coating material well above its melting point by any suitable heating means such as a steam jacket, or, as here shown, electric heating elements 35 mounted on the exteriors of the sloping sides of the reservoir.

The coating composition, or its ingredients, are from time to time put into the outer chamber 30 through the top of the reservoir in solid or powdered form. The partition 34 acts as a screen to prevent the passage of the composition into the inner chamber until the composition has been melted and lumps eliminated. I prefer to employ an agitator 36. It may be carried by a shaft 37 depending from a bevel gear box 38 at the top of the reservoir, the agitator shaft being driven by a motor 39.

When there is no wire in the applicator 15 the melted composition would run out through the bores 25b and 26b. To avoid this I provide an automatic control for the valve to shut it off when the wire has run out. This control preferably is a sheave 40 riding on the wire 10 and carried at one end of a lever 41 which is pivoted at 42 on a bracket from the frame 14. The other end of the lever 41 is pivotally connected to the slotted end 43 of a link 44 connected to the end of the valve lever 45. The slot 43 in the link 44, as shown in dotted lines in Fig. 1, permits a certain up and down movement of the rider sheave 40 to compensate for the different elevations of the wire 10 between the full and empty positions of the supply reel 11, without actuating the valve. However when the wire runs off the supply reel 11, the rider lever 41 drops down to a vertical position and pulls the valve lever 45 over to closed position. This immediately cuts off further supply of coating composition to the applicator chamber 27 and leaves but a relatively small amount to run out of the bores of the dies. This slight loss may be caught by drip pans not shown. In threading wire from a new supply reel, the rider sheave is not lifted up to position on the wire until the threading has been completed and the wire is ready to be pulled through the applicator.

The body of the applicator and the dies are maintained at a temperature well above the melting point of the coating composition by electric cartridge unit heaters 46 inserted in holes drilled transversely through the body. As shown in Fig. 4 these heat units are disposed close to the dies. The dies fit the opening 24 in the body snugly so there is a good heat transfer from the body to them. One pair of cartridges is disposed opposite the anterior die 25, one opposite the chamber 27 to keep the contents hot and two pairs are disposed opposite the discharge die 26. It is particularly advisable in my method to keep the surface of the discharge bore 26b hot enough throughout its length to melt the coating composition.

In the embodiment of my invention here disclosed, the wire supplied to the applicator by the supply reel 11 consists (see Fig. 8) of the usual copper conductor 50, layer of rubber insulation 51, fabric braid 52 and impregnation 53. Many features of my invention are not particularly limited to the composition of the impregnation.

Among other impregnation materials which may be used, is the usual stearin pitch with little or no other ingredients added. My coating need not be applied directly over the impregnation. For example, as previously mentioned, a water proofing impregnation of asphalt and pitch is sometimes used with a coating of stearin pitch over it. Many features of my invention are applicable to the application of the final coating over this intermediate coating of stearin pitch. However one feature of my invention is concerned with the composition used as the impregnation. The material with which the wire may have been impregnated before being passed through the coating apparatus of my invention may be 35% stearin pitch, 15% of paraffin, 10% of other waxes, 15% of natural or synthetic resin and 25% of filler. This composition contains sufficient paraffin or other wax-like material to render the surface of the impregnation non-sticky and to afford a sufficient lubrication to permit its being drawn through conduits without danger of abrasion,—without losing its relatively flame-retarding quality. As here shown the wire is fed to the coating apparatus from a reel of wire which has previously been impregnated and of course cooled to room temperature. Should wire be fed to my coating apparatus directly from the impregnating apparatus, the wire should, for the fullest advantages of my apparatus and method, be properly cooled for reasons heretofore and later explained.

The coating composition employed is preferably of the same composition, except for the addition of pigment if the wire is to be colored. For certain colors, the filler of the composition may be replaced by pigments of such bulk that they themselves form fillers.

My coating method and the operation of my apparatus is as follows: A previously impregnated and cooled wire 10 is unwound from the supply reel 11, passed over the sheave 13, through the aligned bores 25b and 26b of the dies of the applicator 15, through the water tank 16, around the sheaves 18 and 19, over the sheave 20 and to the winding reel 21. Then the rider sheave 40 is lifted on to the wire 10. This opens the valve 33 and permits the melted wax to run down into the chamber 27 of the applicator. The bore 25b being somewhat larger than the wire 10, air is displaced through the bore 25b by the melted coating composition entering the chamber 27 until the level of the liquid seals off the lower edge of the bore 25b. The head of liquid composition in the reservoir 30 compresses the trapped air to raise the liquid level to a slightly higher level. I have not found it necessary to provide a vent from the top of the chamber 27 to the height of the liquid level in the reservoir 30 to remove the trapped air.

The winding reel 21 is then set in operation pulling the wire rapidly through the applicator 15. Once the wire is in motion, there is no leakage of coating composition through the anterior bore 25b, despite the clearance between the bore and the incoming wire. This is because the wire, being cold immediately starts to congeal some of the melted composition on to its surface, thereby restricting the amount of clearance. The factor of surface friction between the melted composition and the congealed composition in so small an annular region, together with the speed of the incoming wire, preclude the melted composition flowing back all of the way through the length of the bore 25b.

Unless some means be provided for maintaining a constant speed (the expense of which I have not found necessary), the speed of the wire will vary because of the increasing diameter of the coil as the wire is wound. I find however that the speed used in wire treating practice is satisfactory, ranging from two hundred to three hundred feet per minute at the start, and four hundred to five hundred feet per minute at the end, of the conventional five thousand foot run, with my method, this speed may also be substantially increased.

The melting point of the composition described will range between 150° and 180° F. The reservoir is preferably maintained at a temperature of about 250° and the applicator at about 300°.

The incoming wire being relatively cool—at room temperature—a layer of the melted coating composition will, as previously described, be congealed upon the surface of the wire as it passes through the chamber 27. In Fig. 8 this congealed layer is illustrated somewhat diagrammatically. The wire passes through the relatively short chamber 27 so quickly that the congealed layer, I believe, continues to accumulate through the length of the discharge bore 26b. The wire is not in the chamber 27 or in contact with the melted composition long enough for the cold wire to be heated even at its surface to any appreciable extent. Consequently the congealing process continues throughout the passage of any given section of the wire through the applicator. The entire coating, it will be borne in mind, is only a few thousandths of an inch thick, the thickness in the diagram of Fig. 8 being exaggerated for clarity.

Because the die is kept hotter, even at the surface of the discharge bore 26b, than the melting point of the coating composition, a free fluidity of the composition will be insured at the surface of the bore, despite the congealing action. This prevents the layer of congealed coating material building up to the full diameter of the bore while the wire is in the bore. No deposit can build up on the surface of the bore tending to restrict its effective size. By maintaining an outer region of melted fluid coating compound throughout the length of the discharge bore 26b, the wire is insured an excellent lubrication in its passage through the bore, with the result that greater speed can be obtained and less tension is required on the wire.

As suggested by the diagram of Fig. 8, the various factors—the temperature of the incoming wire, the temperature of the die 26, the consistency of the coating material, the speed of the wire, the length of the die 26, etc.—are so controlled that, by the time a given section of wire reaches the discharge end of the bore 26b, the layer of congealed coating material has built up to such a diameter as to leave only a minimum clearance from the surfaces of the bore 26b for the outer film of fluid material. Thus as the wire emerges from the discharge end of the bore 26b it comprises the core of impregnated wire, a coating of congealed material and a surface film of liquid melted material. The surface film is preferably of considerable lesser thickness than the coating of congealed material. The emerging film of melted material is so thin and evenly distributed that in the short interval of time available the force of gravity does not have an opportunity to concentrate the melted material on the underside of the wire to any appreciable extent. The emerging film of melted coating

congeals before such aberration can take place to any appreciable extent. The rapid congealing of the emerging liquid film is due to three factors: First, the continued absorption of heat by the relatively cool body of the wire, second, the chilling effect of the air about the emerging liquid film and third, the slightly subsequent immersion in the tempered water bath 17.

As here illustrated, the discharge bore 26b is of slightly less diameter than that desired for the wire after coating. Preferably it is the same as that of the uncoated wire. In such case the thin film 55 of the melted coating material is definitely drawn into the discharge bore 26b between the wire and the bore. The thickness of this film is not added to the radius of the resulting wire but is absorbed by the material of the wire assembly. This is chiefly by the impression of the braid into the rubber insulation. Thus the emerging wire as soon as the liquid coating has set after it leaves the hot discharge bore 26b, is of the same diameter as the incoming wire. To a certain extent, depending upon the characteristics of the rubber insulation and of the braid, the diameter of the discharge bore 26b may be even less than that of the incoming wire. Ordinarily it is of no object to have it less, except it may be necessary to offset the tendency of the wire assembly to come back toward its normal size after compression.

By inclining the direction of travel of the wire through the applicator, the wire may continue on down through the surface of the water and through the body of the water so that before it reaches the sheave 18 the coating is tempered and set. By that time the contact with the sheave will not destroy the slick "flame" finish given the wire. It is important to a proper finish of the wire that the coating be set before contacting a sheave or other part. This has presented a serious problem in the past, which has often been met by running the coated wire from a discharge die through a long air space before it touches a sheave or other part. This has required a considerable amount of factory space. It has also involved a long length of wire in the coating apparatus as a whole at any given instant. The length of wire required to "thread" a new reel of wire in the coating apparatus is generally of an unworkmanlike appearance both at the beginning and the end of the run of a reel of wire. One feature of my invention is that this "threading" length, which may be imperfect, is greatly reduced.

If desired, the wire may be polished by the usual leather or rope wiper after the initial immersion in the water. Preferably, as shown in Figs. 1 and 2, I use a hot die 56 arranged between the sheaves 18 and 19, so that the wire is immersed again following the action of the finishing die.

The inclination of the wire as it passes through the applicator may be increased or decreased as desired—even being increased to the vertical. As it approaches the vertical, the anterior die becomes unnecessary if the chamber 27 is placed at such a height or made of such a length that the head of melted material in the reservoir 30 does not cause the melted material to overflow the chamber.

The ultimate over-all diameter of the coating is substantially, but not wholly, determined by the diameter of the discharge bore. Within the length of the discharge bore there is a certain frictional lag between the film of melted material

and the walls of the bore. This tends to hold back some of the liquid film, with the result that the liquid film, when it emerged from the end of the discharge bore, would be a trifle less than the diameter of the bore. This tendency however is largely offset by the pressure of the head of liquid composition in the reservoir which forces the liquid film out against the frictional lag. The various pertinent factors—the pressure head, the speed at which the wire travels, the viscosity of the melted material and the thickness of the congealed coating in relation to the thickness of the liquid coating at the discharge end of the bore—are preferably so balanced as to produce a resulting over-all diameter of the coating the same as that of the bore.

For different sizes of wire, or for different thicknesses of coatings, anterior and posterior dies having bores of different sizes are readily substituted. Slight variations in the thickness of the coatings on a given size of wire may be produced by varying whichever of the previously mentioned factors is most convenient.

While I prefer wherever feasible to use substantially the same composition (except for pigment) in the impregnation as in the coating, it is expedient, when the coating is to be of certain colors, to substitute a coating composition where the active flame-retarding ingredient is something other than a very dark pitch such as stearin pitch. The expediency of this substitution is particularly true of a white wire, and to some extent with blue and yellow wires if it is essential that the colors be bright. In such instances a base may be substituted which has a characteristically light color. Such substitution however should still preserve for the coating the characteristics of flame-retarding, non-stickiness; sufficient slipperiness and "slick" finish. The advisability or expediency of such a substitution may be determined by balancing, on the one hand, the added cost of the substitute as compared with the pitch-and-wax composition previously described, against, on the other hand, the increased cost of the relatively expensive blue, yellow or white pigments in the quantities which would be required satisfactorily to overcome the blackness of the pitch. Where substitutes are used for the coating composition, waxes, resins or other ingredients may be added to control the viscosity and melting point preferably to the same melting point as that of the impregnation.

I have previously mentioned that one of the advantages in treating the braided wire in two processes—an impregnation and a coating—even though the impregnation composition and the coating composition be the same except for pigment, is the saving in the cost of relatively expensive pigment. This however is not the only advantage. An important advantage, apart from the phase of color, is this: If the impregnation and coating were combined into a single operation, the relatively large mass of hot melted material absorbed by the braid would so raise the temperature of the wire at the region of the braid as to preclude an effective congealing of the material toward the region of the ultimate diameter of the finished treated wire. This would tend to prevent bringing the layer of congealed material sufficiently close to the surface of the discharge bore to secure the greatest benefits of my method whereby an accurately controlled layer of material is deposited for a considerable

thickness beyond the over-all diameter of the braid.

In my coating method a discharge bore of some appreciable length is advisable for these reasons:

- 5 The surface of a short bore would be chilled more rapidly than the necessary heat would well be applied to it; the long annular space between the wire and the die affords a more accurate metering of the material being coated; the long bore gives 10 an advantageous "ironing" effect; a long bore permits greater speed; if the bore were short, there would be less region of frictional lag of the melted film, with a result that the head of liquid material could not be so well balanced by the frictional lag, and hence the fluctuation in the liquid 15 head by the addition of the material to the reservoir from time to time would too readily vary the outflow of melted material from the discharge bore; and, as the process of building up the layer of congealed material could not be carried forward to any appreciable extent within the length of a short bore, it would be difficult if not impossible so to control the thickness of the layer of congealed material that by the time it got to the 20 short bore it would leave an intervening space of the proper thickness for the film of melted material—if this space were insufficient there would be a damming up at the entrance end of the short bore which would block the flow of melted 25 material, and if the space were too great, the layer of melted material emerging from the short discharge bore would be too thick to be congealed before it had flowed to the underside of the wire to form a coating of eccentric cross section and perhaps also to permit some of the liquid material to drop off the wire.

When the wire is to be coated with not merely one primary color, but a combination of colors arranged as superposed coatings, an additional 40 color coat is placed on the wire. Referring again to Fig. 8, I have shown a secondary coating 54' of red, for example, placed over the primary coating 54 of yellow, for example. The secondary coating may be applied in the same way as was 45 the primary coating.

In Fig. 9 I have shown an alternative form of two color wire where the secondary color is applied as a streak or plurality of streaks 54" instead of a complete secondary coating. This has 50 the advantage of readily identifying the wire without removal of any coating.

In Fig. 10 I have shown a modification of the applicator adapted to apply a pair of diametrically spaced streaks of colored coating material. 55 Here a pair of diametrically opposed longitudinal members 60 afford cylindrical opposed surfaces of 90° arcuate cross section. The members extend from the mouth of the anterior die 25 to the discharge end of the discharge die 26 and in 60 contact with the surface of the wire to prevent the liquid coating composition being applied, from coming in contact with corresponding arcuate portions of the wire. Thus the coating material is applied as a pair of streaks 54" only to those 65 regions of the wire which are not thus massed out by the member 60. If the arcuate regions of the discharge bore 26b in line with the unmassed region be arranged on a diameter substantially that of the incoming wire, the streaks 54" will 70 be imbedded or compressed into the wire assembly for the same reason, as previously described, that the compression die applies a coating without enlarging the diameter of the wire.

While I have described and illustrated this 75 specific method, apparatus and article, I contem-

plate that many changes may be made therein without departing from the scope or spirit of my invention.

I claim:

1. A coating apparatus comprising a heating reservoir for melted coating material, an applicator casing, a chamber therein, means for conducting melted coating material from the reservoir to the chamber, aligned anterior and posterior bores in the casing and disposed in a 10 downward oblique position, the chamber being disposed between the bores, means for heating the casing to maintain the coating material in the chamber in melted state and for maintaining the surface of the posterior bore at a higher 15 temperature than the melting point of the coating material, the posterior bore being of approximately the diameter of the desired coated article and a tank of tempering liquid disposed at a lower elevation than the bores and at such position that the surface of the liquid is obliquely 20 intercepted by an extension of the axis of the aligned bores, means for feeding to the anterior bore the strand-like article to be coated and means for pulling the wire through the applicator and the tempering liquid, the applicator being constructed and arranged to keep the wire out of contact with any solid in passing from the 25 discharge bore into the liquid.

2. In a wire coating apparatus the combination of a receptacle for melted coating material, means for guiding a wire therethrough including a discharge bore leading from the receptacle of approximately the diameter of the desired coated wire and means for maintaining the surface 30 of the discharge bore at a higher temperature than the melting point of the coating material throughout its length whereby the wire will 35 emerge therefrom enveloped in a film of melted material.

3. A wire coating apparatus comprising a metallic body having a hole therethrough, the body being split along the hole, a cylindrical anterior die member disposed in the one end of the hole and making a fluid tight seal therewith, a posterior die member disposed within the other end of the hole and making a fluid tight seal therewith, the adjacent ends of the die members being spaced apart leaving a chamber, aligned 40 wire receiving bores through the anterior and posterior die members, the posterior bore being of approximately the same diameter as desired of the coated wire, conduit means for supplying melted coating material to the chamber and the bore of the posterior die, and means for maintaining the walls of the chamber and the surface of the bore of the discharge die at temperatures above the melting point of the coating 45 material.

4. An apparatus for coating wire comprising an anterior sheave for guiding the wire, a tank of tempering water, a posterior guiding sheave for the wire immersed in the water in the tempering tank, the sheaves defining a downwardly inclined position for a straight-line reach of wire, 60 a receptacle for melted coating material disposed intermediate the sheaves and above the surface of the water, the receptacle having a discharge bore of approximately the diameter of the desired coated wire with the axis of the bore aligned 65 with the center line of the reach of wire as determined by the sheaves, and means for maintaining the surface of the discharge bore at a temperature above the melting point of the coating material whereby the wire emerges from the 70 75

discharge bore enveloped in a film of melted material and directly into an intervening air gap between the discharge bore and the surface of the water.

5. A wire coating apparatus comprising a metallic chamber body for containing wax-like coating material, a wire inlet thereto, a die body in thermal contact with the chamber body and forming a discharge bore therefrom constituting a discharge die, a heating device applying

heat to the chamber body to maintain the material thereon above a melting temperature, and another heating device applying heat to the die body, the second heating device being at a shorter thermal conduction distance from the discharge bore than is the first heating device and being constructed and arranged to maintain the discharge bore at a temperature higher than the melting point of the material.

ALBERT T. CANDY, JR. 10
